UNITED STATES PATENT OFFICE.

ATHERTON D. CONVERSE, OF WINCHENDON, MASSACHUSETTS.

SPINNING-TOP.

1,324,997.

Specification of Letters Patent. Patented Dec. 16, 1919.

Application filed June 15, 1918. Serial No. 240,145.

To all whom it may concern:

Be it known that I, AETHERTON D. CONVERSE, a citizen of the United States, and resident of Winchendon, Massachusetts, have 5 invented certain new and useful Improvements in Spinning-Tops, of which the following is a specification.

My invention relates to the class of spinning tops in which a spring is wound by turning the body and a handle in relation to each other. Such forms of tops have been used with ratchet means for holding the spring in its wound or partially wound condition until it is desired to spin the top, an 10 example of this type being shown in Letters Patent of the United States granted to Schoell, No. 1,253,195, or such tops have been proposed for use without ratchet means, as in the patent of Haag June 21, 1891, No. 15 453,473, but in this form of top it requires the use of both hands not only to wind but to hold the parts in the wound-up relation until the top is set off.

With my improvement the top can be held 20 in its wound or partly wound condition by the fingers which grasp the winding knob or handle, so that not only can the winding-up operation be quickly and conveniently performed, but also the top may be held in the 25 one hand in its fully wound up condition, placed in position for spinning and set off by simply releasing it from the grasp of the fingers of one hand.

The invention is shown in the accompanying 30 drawing, in which,

Figure 1 is a vertical sectional view.

Fig. 2 is a top plan view.

Fig. 3 is a detail of a modified arrangement of spinning pin.

40 The body consists of an upper sheet metal shell 1, and a lower shell section 2 united by turning a flange 3 of the lower shell section onto the flange of the upper shell.

A spindle 4 is journaled in the body, its 45 lower end having a socket receiving the upper extension of the pin 5.

This pin is suitably united to the body, being shouldered at 6 to bear on a washer 6' on the lower side of the shell and the lower 50 end of this pin furnishes the spinning point. There is also an interior washer 6''. At its upper end the spindle passes through an opening in the top of the shell, and at this point the spindle is reduced forming a shoulder 7, which bears on the underside of 55 the top of the shell and thus the spindle is

held against longitudinal displacement upwardly while downward longitudinal displacement relative to the body is prevented by the lower end of the spindle resting over 60 the top of the pin 5, as above described. The winding spring is attached to the body or shell at its upper end, and at its lower end it is united with the spindle, so that the spindle with the spring is assembled with the 65 upper shell section as one body and only the spinning pin is assembled with the lower shell section. In completing the assembly it is only necessary to place the upper shell, with the spindle handle and spring carried 70 thereby, in engagement with the lower shell section, so that its horizontally extending flange will rest on the shoulder within the flange 3 of the lower shell and then by bending this flange over onto the flange of the upper shell the connection will be completed. The upper end of the spindle carries a handle 75 portion which may consist of a knob 8 fixed thereto by a pin or otherwise.

This handle may be slightly tapered down- 80 wardly so that the fingers that grasp it will be so positioned that their tips will press down upon the upper surface of the adjacent portion of the body or shell of the top and the fingers will thus act as the detent 85 means to hold the body against rotation under the pressure of the spring in the spinning direction. The spindle, as before stated, is held against longitudinal displacement in relation to the body and consequently the handle or knob is maintained in 90 a fixed or definite position relative to the adjacent surface of the body, except of course that the handle can rotate, in the plane in which it lies. In other words the handle has

95 no displacement in the direction of its axis and consequently the fingers which grasp it by reaching down along its sides and below the same can engage with certainty and with the desired degree of pressure upon the surface of the body and thus act as detent means. The handle is preferably substantially circular in form though it may have flat spots on its periphery to insure a better hold. It is of sufficient depth to present a 100 comparatively wide peripheral surface at all points to afford a proper extent of gripping surface for the fingers, and it is of sufficient diameter to afford a bearing surface or periphery to be gripped by three fingers, the 105 thumb, index and second finger, and also its diameter is such that these fingers will be 110

comfortably separated and the points at which they bear on the top of the shell will be substantially evenly spaced or distributed at say 120° apart and a natural grasping action of the fingers will be provided for, and by providing such a handle which will insure engagement of the fingers with the top of the body at widely separated points located a considerable distance out from the axis of the top a long leverage is afforded opposing the tension of the spring, and a comparatively slight pressure of the fingers will give sufficient resistance to prevent the spring from reacting until the operator releases the knob or handle for the spinning operation. I employ a spring which is light and easy in its action, and one of considerable length which is of advantage, because the detent pressure of the fingers on the body thereby can be lighter than with a short stiff spring and furthermore the spring takes a longer time in unwinding and thus the user does not have to exercise the same degree of care in letting go in order to get a proper spinning action. In other words instead of letting go suddenly to get the "kick" of the spring he can let go more gradually as the spring will still have power therein after it starts to unwind. This is especially desirable because the top will be used mostly by small children, who naturally will not be so exact as to the manner of releasing the handle.

I have stated above that the handle may have flat spots on its edge or periphery. It may be formed of shapes other than circular, such as square, octagonal, or the like, but in these cases like that illustrated it presents an edge to be grasped by the fingers, said edge lying in a substantially horizontal plane and extending about the vertical axis of the top, so that the fingers engaging this edge at different points about the handle and extending down therefrom will engage or bear upon the permanently positioned juxtaposed surface of the body to act as detents for holding the latter against rotation in the spinning direction, while the top is being wound in the hands, and also while the top is being placed in position by one hand. The spinning pin instead of being formed as shown in Fig. 1 and carried by the lower section of the shell may be carried by the spindle itself, as shown in Fig. 3 at 5*. This pin is in effect a part of the spindle being driven into the spindle and extending down therefrom through the central opening in the lower shell to be exposed below said shell, and to bear on the surface supporting the top in spinning.

One advantage of this construction is that the spinning point, spindle and spring, or in other words all of the parts of the top, excepting the lower section of the shell are

assembled or combined as one body and this assembly is effected before the sections of the shell are secured together, so that in completing the top after the various parts are assembled in connection with the upper section of the shell it is only necessary to thread the lower section of the shell onto the spinning pin, and then unite the two sections by their flanges.

There is another advantage which accrues from the spinning pin just described in that there is less friction because the bearing at the spinning pin between it and the lower section of the shell is only that which arises from the thickness of the tin.

In the construction shown in Fig. 1, however, the spindle turned on that portion of the pin which projected up into the socket thereof. The less friction the top has when it is performing its backward or spinning movement, as to its body in relation to the spindle, the greater speed it will attain and the longer it will continue spinning and in the form of top shown in my application filed June 13, 1918, No. 239,772, in which a ratchet is employed between the end of the spring and the spindle the longer it will continue to rotate while being held in the hand and therefore the easier it will be to get the top onto the table or other surface and start its spinning on time. This construction of the spinning pin carried by and inserted in the spindle is less expensive to make and is more durable than a construction such as shown in Fig. 1, in which the spinning pin is secured to the thin material of the lower section of the shell.

What I claim is:—

1. A spinning top comprising a body, a spindle mounted therein, a spring connected to the spindle and body to be wound by relatively turning said parts, said spindle having a winding handle above said body held against axial displacement relative to the body, and in juxtaposition thereto, presenting a laterally directed edge portion extending substantially uniformly about the vertical axis to be grasped by the fingers, substantially uniformly at all points, which edge portion overlies the surface of the body, enabling the fingers extending down from said edge portion to bear on said permanently positioned juxtaposed surface to act as detents for holding the body against rotation in the spinning direction as the top is being wound, while supported in the hands, and while the top is being placed by the one hand in position to spin, substantially as described.

2. A spinning top having a body, a spindle, a spring, a handle for the spindle and a spinning pin inserted in an opening in the lower end of and carried by the spindle and extending through the bottom of the body

to project therefrom, substantially as described.

3. A spinning top having a body composed of upper and lower sections united together, a spindle within the body, a spring, a handle for the spindle and a spinning pin carried by the spindle and extend-

ing through the lower section of the body, the said spindle, spring, handle and spinning pin all being assembled with the upper section of the body, substantially as described. 10

In testimony whereof I affix my signature.
ATHERTON D. CONVERSE.
